UNITED STATES PATENT OFFICE.

THOMAS CORWIN HALL, OF ANAMOSA, IOWA.

CUSPIDOR.

Application filed May 18, 1925. Serial No. 31,140.

To all whom it may concern:

Be it known that I, THOMAS CORWIN HALL, a citizen of the United States, residing at Anamosa, in the county of Jones and State of Iowa, have invented certain new and useful Improvements in a Cuspidor, of which the following is a specification.

The present invention relates to cuspidors, and more particularly to cuspidors of the fountain or self-cleansing type.

An object of this invention is to provide a cuspidor of this type which has a curtain of water flowing over the main inner parts to maintain them in a clean and sanitary condition at all times.

Another object of this invention is to provide a device of this character which embodies all of the above features, and is also capable of being suddenly washed or flushed at will.

A further object of this invention is to provide a cuspidor which may be attached to a sewer outlet and which embodies a trap to prevent any sewer gas from escaping upwardly through the device.

A still further object of this invention is to provide a device of this type which includes sieve or catcher for catching large particles which would have a tendency to clog the outlets thereof.

The above and various other objects and advantages of this invention will in part be described in, and in part be understood from the following detailed description of the present preferred embodiment, the same being illustrated in the accompanying drawing, wherein:

Fig. 1 is a transverse section taken vertically through a device constructed according to the present invention.

Fig. 2 is a detail top plan view of the same.

Fig. 3 is a transverse section taken through the device on substantially the line 3—3 of Fig. 1, and

Fig. 4 is a transverse section taken on substantially the line 4—4 of Fig. 1.

Referring to the drawing, 10 designates a support for the cuspidor which may be the floor or a building or the extended arm or the like of a dental chair or the like. The body 11 comprises a cylindrical casing or the like and preferably rests at the bottom thereof upon the support 10. The base 12 of the casing 11 extends inwardly from the outer edge thereof, and has a horizontal

opening 13 therethrough. The intake side of the opening 13 extends downwardly through the base 12, and is attached to the source of water supply 14, a valve 15 or the like being interposed between the base and the source of water. The valve 15 is preferably opened by pushing the handle thereof downwardly so that it may be operated at will by the pressure of a hand or foot, depending upon the location of the cuspidor.

An uptake opening 16 is preferably positioned in the base 12 opposite the intake opening, and a pipe 17 extends upwardly therefrom, being connected at its upper end to a ring-shaped pipe or shower 18. The ring 18 preferably rests upon the upper edge of an inwardly extending flange 19 which is secured to the inner side of the casing 11 at a point spaced downwardly from the upper edge thereof. The ring 18 has a plurality of downwardly extending holes 20 through the lower side thereof so that water entering the ring will be sprayed downwardly. The opening 16 at its lower end joins the opening 13 so that water entering opening 13 will flow upwardly to the shower 18.

An arched trap 21 is mounted upon the base 12, the outer end of the trap 21 terminating in the inner side of the casing 11, and the inner side of the trap being secured to the upper end of an inner casing or outlet chamber 22. The chamber or casing 22 at its lower end has an outwardly extending flange 23, and is adapted to be secured by bolts 24 or the like to a sewer pipe 25. The plane of the inner end of the trap 21 rises above the plane of the outer end thereof for purposes which will hereinafter be more fully described.

A downwardly arched shield 26 is mounted upon the upper end of the casing 11 and is held in position by a downwardly extending ring 27 which fits within the inner side of the casing. The shield 26 is preferably loosely mounted upon the upper end of the casing 11 so that when desired it may be removed to facilitate the cleaning of the inside of the casing or adjustment of the component parts of the cuspidor. The inner end of the shield 26 extends over and in spaced relation thereto the ring 18 so that any sputum or the like which may strike the shield will not come in contact with the ring 18.

The base 12 has a plurality of upwardly extending openings or holes 28 which are

connected at their lower ends with the opening 13, and their upper ends open into the trap 21 so that some of the water entering the opening 13 will go upwardly through 5 the openings 28 and into the trap 21. The openings 28 are preferably slanted inwardly so that the water going therethrough will be forced toward the inner edge of the trap. A plurality of dividers 29 are mounted upon 10 the trap 21 and extend upwardly therefrom, the inner edges of the dividers meeting at a point in substantially the center of the upper plane of the casing 22 so that the water being forced toward the inner edge of the 15 trap 21 will not flow over the top of the casing, but must fall downwardly thereinto.

One of the dividers 29 is preferably thicker than the other dividers as shown at 20 30, and has an opening 31 therethrough, the lower end of the opening being connected to an intake pipe 32, which is also connected to the source of water supply 14. A valve 33 is interposed in the line 32 intermediate the source of supply, and may be operated 25 by turning the handle or knob thereof. A conical shield 34 is mounted upon the upper edge of the dividers 29 and 30, the base of the shield extending into the area of the trap 21 and below the outer end thereof. 30 The upper end of the shield 34 has a downwardly extending opening 35 therethrough which opens into the upper end of the opening 31, and forming a continuous opening from the lower end of opening 31 to the 35 apex of the shield 34. A second conical shield 36 having an inner opening 37 is mounted upon the upper end of the shield 34. The inner side of the shield 36 deflects the water entering the opening 37 downwardly, the water passing through a plurality of openings 38 which extend through the bottom of the cone 36 adjacent the outer edge thereof.

At the upper end of the outer edge of the 45 trap 21 there is provided an inwardly extending flange 39 for supporting the outer edge of a ring-shaped sieve or screen 40. The inner edge of the sieve 40 detachably rests upon the shield 34 at a point spaced 50 upwardly from the lower edge thereof. The sieve is adapted to prevent large particles from entering the trap 21 or the casing 22, and is readily removed for cleaning purposes.

In the operation of this device, the valve 55 60 65 70 75 80 85 90 95 100 105 110 115 120 125 130 135 140 145 150 155 160 165 170 175 180 185 190 195 200 205 210 215 220 225 230 235 240 245 250 255 9999

desired open position. The water flowing downwardly on the shield passes through the sieve 40 and drops into the trap 21. Upon filling up the trap 21 the water overflows at the inner edge thereof and into the 70 casing 22, from whence it enters the sewer opening through the sewer pipe 25. As the upper edge of the casing 22 rises above the plane of the lower end of the shield 34, the trap 21 will always remain filled with water, and thus prevent any sewer gases from rising into the 75 cuspidor. It has been found desirable to occasionally give the interior of the cuspidor a thorough cleansing or flushing, and in order to accomplish this the handle of the valve 15 is pressed downwardly to permit the water to flow into the opening 13 in the base 12. The valve 15 is preferably opened fully so that the full pressure of the incoming water is carried 80 into the opening 13 a portion of the water enters the openings 28 and forcibly throws the water in the trap 21 against the dividers 29 and 30 and from thence into the casing 22. The main body of the water entering the opening 13, however, passes upwardly into the opening 16 and into the ring or shower 18, where it is sprayed downwardly against the inner side walls of the casing 11 and upon the shield 34. This cleansing or flushing process thoroughly cleans the inside of the cuspidor, and if any large articles have been caught by the sieve, they may be readily removed by lifting the sieve out and brushing 85 or otherwise cleaning it. It will be seen from the above that this device is sanitary in every respect, and for general appearances the component parts thereof may be coated with enamel or the like 90 so that any foreign objects or matter will be readily disclosed. It is, of course, understood that various changes and modifications may be made in the details of construction and design of the above specifically described embodiment of the invention without departing from the spirit thereof, such changes and modifications being restricted only by the scope of the following claims: What is claimed is:

1. A sanitary cuspidor comprising a body, a trap mounted within said body, an outlet casing secured to said trap, baffle plates mounted upon said casing and within said trap, a shield secured to said baffle plates, one of said baffle plates having an opening therethrough, said shield having an opening through the upper end thereof and extending into the opening in said baffle plate, a deflector on said shield, means for spraying water within said body, and means for attaching said outlet casing to a sewer.
2. A sanitary cuspidor comprising a casing, a water trap within said casing, an outlet

let casing secured to said water trap and adapted to receive water therefrom, a plurality of baffle plates mounted upon said outlet casing and said water trap, one of said baffle plates having an opening therethrough for receiving water from a source of water supply, a conical shield mounted upon said baffle plates and having an opening through the upper end thereof registering with said opening in said baffle plate, a deflector secured to the upper end of said shield and adapted to deflect the water upon the surface of said shield, a strainer positioned within said trap for preventing the clogging thereof, and means for flushing the inside of said casing.

3. A sanitary cuspidor comprising a casing, a water trap within said casing, an outlet casing secured to said water trap and adapted to receive water therefrom, a plurality of baffle plates secured to said outlet casing and said water trap, one of said baffle plates having an opening therethrough for receiving water from a source of water supply, a shield mounted upon said baffle plates and having an opening through the upper end thereof registering with said opening in said baffle plate, a conical deflector secured to said shield at its upper end, said conical deflector having downwardly extending openings for throwing the water upon the surface of the shield, means for straining the fluid entering said trap, a sprayer mounted within said casing adjacent the upper end thereof, means for connecting said sprayer to a source of water supply, flushing means within said trap for forcing the water therein upwardly against said baffle plates and into said outlet casing, and means for mounting said outlet casing upon a sewer connection.

4. A sanitary cuspidor comprising a casing, a water trap within said casing, baffle plates within said trap, an outlet casing secured to said trap, said baffle plates terminating at their inner ends over the upper end of said outlet casing, a shield mounted upon said baffle plates, means for spraying

water upon said shield, and means for flushing said trap.

5. A sanitary cuspidor comprising a casing, a water trap within said casing, an outlet casing secured to said trap at its inner edge, baffle plates within said trap and terminating at their inner ends over the upper end of said outlet casing, a shield mounted upon said baffle plates, means for throwing a film of water upon said shield, means for flushing said trap, means for spraying the inside of said casing simultaneously with the flushing of said trap, and an upper shield mounted upon the upper end of said casing for protecting said spray means.

6. A sanitary cuspidor comprising a casing, a water trap within said casing, an outlet casing secured to said trap, a plurality of baffle plates within said trap and terminating at their inner ends over the upper end of said outlet casing, a conical shield mounted upon said baffle plates, means for throwing a continuous film of water upon said shield, flushing means for flushing said trap, spray means operable simultaneously with said flushing means for spraying the inside of said casing, means for protecting said spray means, and means for connecting said outlet casing to a sewer.

7. A sanitary cuspidor comprising a cylindrical casing, a water trap within said casing, an outlet casing secured to said trap, baffle plates mounted within said trap and terminating at their inner ends over the upper end of said outlet casing, a conical shield mounted upon said baffle plates, means flowing a film of water upon said shield, flushing means for flushing said trap, spray means adapted to be operated simultaneously with said flushing means for spraying the inside of said casing, means for protecting said spray means, a strainer mounted within said cylindrical casing and upon said shield for preventing large particles from entering said trap, and means for connecting said outlet casing to a sewer.

THOMAS CORWIN HALL.
